Primary Examiner — Richard E Chilcot(74) Attorney, Agent, or Firm — Sughrue Mion, PLLCCLAIM

The ornamental design for dispensing heads for dispensers, as shown and described.

DESCRIPTION

2. Dispensing heads for dispensers

2.1 : Perspective

2.2 : Front

2.3 : Back

2.4 : Right

2.5 : Left

2.6 : Top

2.7 : Bottom

1 Claim, 7 Drawing Sheets(56)
